Primary Examiner — Nathan M Johnston(74) *Attorney, Agent, or Firm* — Carter, DeLuca & Farrell LLP**CLAIM**

The ornamental design for a multi-purpose caddy, as shown and described.

DESCRIPTION

FIG. 1 is a perspective view of a multi-purpose caddy in accordance with the present design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective view of the design embodied in FIG. 1 illustrating a non-limiting use in an unclaimed environment.

The caddy is shown with a symbolic break in its length. The appearance of any portion of the article between the break lines forms no part of the claimed design.

The broken lines shown in the drawings illustrate portions of the multi-purpose caddy that form no part of the claimed design.
